(57) **CLAIM**

The ornamental design for an acoustic barrier, as shown and described.

DESCRIPTION

FIG. 1 is a front perspective view of an acoustic barrier of a first embodiment;

FIG. 2 is a front view of the first embodiment;

FIG. 3 is a rear view of the first embodiment, showing the acoustic barrier with a backing sheet;

FIG. 4 is a top view of the first embodiment;

FIG. 5 is a bottom view of the first embodiment;

FIG. 6 is a left view of the first embodiment;

FIG. 7 is a right view of the first embodiment;

FIG. 8 is a rear perspective view of the first embodiment;

FIG. 9 is a front perspective view of an acoustic barrier without a backing sheet of a second embodiment;

FIG. 10 is a front view of the second embodiment;

FIG. 11 is a rear view of the second embodiment, showing the acoustic barrier without a backing sheet;

FIG. 12 is a top view of the second embodiment;

FIG. 13 is a bottom view of the second embodiment;

FIG. 14 is a left view of the second embodiment;

FIG. 15 is a right view of the second embodiment; and,

FIG. 16 is a rear perspective view of the second embodiment.

The acoustic barrier is shown with a symbolic break in its width. The appearance of any portion of the article between the break lines forms no part of the claimed design.
